UNITED STATES PATENT OFFICE.

FRANK GRAY, OF FORT WORTH, TEXAS.

BUILDING-BLOCK CONSTRUCTION.

1,147,015.

Specification of Letters Patent. Patented July 20, 1915.

Application filed March 23, 1915. Serial No. 16,314.

To all whom it may concern:

Be it known that I, FRANK GRAY, a citizen of the United States, residing at Fort Worth, in the county of Tarrant and State of Texas, have invented certain new and useful Improvements in Building-Block Construction, of which the following is a specification.

My invention relates to concrete building blocks and more particularly to means for bonding building blocks together, and the object is to provide building blocks for general building purposes, and more particularly blocks for building silos and water tanks and other air and water tight structures; and a further object is to provide blocks with bonding means which are simple and which can be economically prepared and permanently secured in the blocks.

Another object is to provide vertical sealing joints in the upper and lower faces of the building blocks, and to provide horizontally extending sealing means, and to provide for forming dowels of plastic material to prevent lateral movement of the blocks relative to each other.

Other objects and advantages will be explained in the following description and the invention will be more particularly pointed out in the claim.

Reference is had to the accompanying drawings which form a part of this application.

Figure 1 is a side elevation of several building blocks connected together as hereinafter set out. Fig. 2 is a vertical section of Fig. 1 taken substantially on the line *x—x*. Fig. 3 is a similar view of a single block. Fig. 4 is a perspective view of a block which is a slight variation from the blocks previously shown.

Similar characters of reference are used to indicate the same parts throughout the several views.

A number of building blocks are shown grouped together in Fig. 1. These blocks are stepped as shown more particularly in Figs. 2 and 3 along their longitudinal upper and lower faces. A step (2) is shown on the lower face of a block and a step (3) is shown on the upper face of a block, and the two steps are spaced apart for the purpose of receiving plastic sealing material. The two steps, 2 and 3, thus provide vertical bearings to form a perfect seal between the

upper and lower faces of the blocks, and the step 2 is preferably on the outside of the block so that no moisture can ever enter from the outside of a structure and pass to the inside. The space (4) thus forms a horizontally extending longitudinal cavity having vertical walls between two tiers of the blocks to receive plastic material for sealing purposes. Each block has a curved cavity (5) in each end so that when the ends of two blocks come together a circular vertical cavity is formed through which plastic material may be poured to the longitudinal cavities formed, when one tier is laid upon another.

Means are provided for reinforcing the blocks and locking the same together. Horizontal rods (6) are embedded in the blocks during the molding process. Each rod (6) has an eye or loop (7) in one end and a bent portion (8) projecting from the other end of the block, so that when two blocks are brought together, end to end, the bent terminal (8) will enter the eye or loop of the rod (6) of the adjacent block. The terminal (8) can then be bent over as shown in Figs. 1 and 2. The bent terminal (8) will thus serve as a tensioning means to draw blocks in close proximity to each other. The upper and lower tiers of blocks are further bonded together; one tier of blocks breaks the joints of the tier above and the tier below and a circular cavity (9) is formed in the upper face of each block, and the circular cavity between the ends of the two blocks of the adjacent tier will register with the circular cavity (9), so that plastic material poured into cavity 5 will go down into the circular cavity (9) to form a bonding means in the nature of a dowel, against longitudinal or lateral movements of the blocks relative to each other. In order that the blocks may be further bonded together, eye-bolts (10) are embedded in the blocks at the time of molding the blocks. The rods 6 are run through the eyes 7 of the eye-bolts 10 before the blocks are molded and a portion of each eye-bolt 10 projects within the cavity 9 and nuts (11) engage the upper ends of the bolts (10) so that when the plastic material is poured down into the cavities, 5 and 9, the nuts will be embedded in the plastic material. Thus the blocks are bonded together directly as between themselves and indirectly as between

the reinforcing bonding rods which they contain, and the wall is made thus solid as if the whole were a monolithic structure.

What I claim, is,—

- 5 A building construction comprising concrete blocks having curved cavities in each end thereof, and a circular cavity in the upper face of each block, the vertical joints of the block being broken, and when two blocks meet, end to end, a circular cavity is formed between the ends registering with the circular cavity of the next block below, bonding devices consisting of a rod embedded horizontally in each block and projecting in the curved cavity of one end and formed into an eye, and the other end projecting through the curved cavity of the other end of the block and formed into a bent terminal, and the bent terminal of one block

engaging the eye of the adjacent block, an 20 eye-bolt embedded vertically in each block and engaging the horizontal rod therein and projecting upwardly into the circular cavity of the block, and a nut engaging the upper end of the eye-bolt and plastic material filling the circular cavity between the ends of each block and extending down into the curved cavity of the next block below, and embedding said bonding devices, including the nuts on the ends of said eye-bolts. 30

In testimony whereof, I set my hand in the presence of two witnesses, this 20th day of March, 1915.

FRANK GRAY.
